CIGARETTE DISPENSER

Arthur Salm, Chicago, Ill., assignor to Arthur Salm Inc.,
Chicago, Ill., a corporation of Illinois

Application November 7, 1956, Serial No. 43,686

Term of patent 14 years

(Cl. D85—2)

Fig. 1 is a perspective view of a cigarette dispenser showing my new design with the drawer and cover partially open;

Fig. 2 is a reduced top plan view of the cigarette dispenser of Fig. 1 with the drawer and cover closed; and

Fig. 3 is an end view of the cigarette dispenser of Fig. 1 with the drawer and cover closed.

I claim:

The ornamental design for a cigarette dispenser, substantially as shown.
